US0D1053962S

(12) **United States Design Patent** (10) **Patent No.:** **US D1,053,962 S**
(45) **Date of Patent:** **** Dec. 10, 2024**

(54) **PUZZLE BOARD**

(71) Applicant: **Zhengmei Zhou**, Puning (CN)

(72) Inventor: **Zhengmei Zhou**, Puning (CN)

(**) Term: **15 Years**

(21) Appl. No.: **29/936,598**

(22) Filed: **Apr. 9, 2024**

(51) LOC (14) Cl. **21-01**

(52) U.S. Cl.

USPC **D21/478; D21/397**

(57) **CLAIM**

The ornamental design for a puzzle board, as shown and described.

DESCRIPTION

FIG. 1 is a front perspective view of the puzzle board, showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a front perspective view of the puzzle board in a disassembled state;

FIG. 10 is a front perspective view of the puzzle board in a disassembled state;

FIG. 11 is a front perspective view of the puzzle board in a disassembled state;

FIG. 12 is a front perspective view of the puzzle board in a disassembled state;

FIG. 13 is an enlarged view of the area labeled 13 in FIG. 1; and,

FIG. 14 is an enlarged view of the area labeled 14 in FIG. 2.

The broken lines in the drawings depict portions of the puzzle board, which form no part of the claimed design. The dot-dash broken lines encircling portions of the puzzle board in FIG. 1 and illustrated in enlarged views in FIGS. 13 and 14 form no part of the claimed design.

1 Claim, 14 Drawing Sheets
